UNITED STATES PATENT OFFICE.

JAMES WEBB SAFFOLD, OF CLEVELAND, OHIO.

WRENCH.

1,415,714.

Specification of Letters Patent. Patented May 9, 1922.

Application filed May 10, 1921. Serial No. 468,206.

To all whom it may concern:

Be it known that I, JAMES WEBB SAFFOLD, a citizen of the United States, residing at Cleveland, in the county of Cuyahoga and 5 State of Ohio, have invented certain new and useful Improvements in Wrenches, of which the following is a specification.

My invention relates to improvements in wrenches, the present embodiment of the 10 invention being particularly designed and adapted for use in the drawing up and loosening of a nut or a bolt head of angular shaped exterior, such for example as "hexagonal" nuts, and the like.

15 My invention further relates to that class or type of wrenches in which the angular shaped nut or head is automatically gripped upon the initial movement of the handle upon the working stroke or impulse given 20 to the head of the wrench, and the article engaged thereby and in which the article or nut is automatically released upon the initial return stroke of the handle for the next working engagement of the nut or article 25 being operated upon.

The primary object is the provision of a generally improved wrench of this class which will be exceedingly simple in construction, cheap of manufacture, and efficient 30 in use.

A further and very important object is the provision of an automatic wrench which will readily adapt its gripping parts to nuts or heads of widely varying forms and sizes, 35 the improved wrench having its working parts so arranged and disposed relative to each other as to centralize the nut and adjacent parts thereby centralizing and distributing the loads and stresses and reducing the 40 liability to damage or disarrangement of the parts to a minimum.

A still further and very important object is the provision of an improved guide head or block provided with a slide having a projecting nut engaging loop movable toward 45 and from the nut engaging portion of the guide head, the slide being provided with a cam thrust receiving portion arranged along the common longitudinal planes of 50 relative movement of the guide head and nut engaging loop, together with a cam pivoted on said head at one side of said plane of longitudinal axis of movement and provided with a curved contact portion so developed as to engage said thrust receiving

portion of the slide along said longitudinal plane or axis of movement throughout all the varying positions of the parts in the article engaging and gripping positions.

A still further object is the provision of 60 a wrench having its parts so arranged and disposed relatively to each other as to centralize and distribute the working strains and stresses thereby preventing any shearing action or jamming or distortion of the 65 parts, the cam and thrust receiving portion of the slide being arranged to centrally return the parts preparatory to taking a new hold or grip for a new working impulse.

With the above mentioned and other ends 70 in view, the invention consists in the novel construction, arrangement, and combination of parts, hereinafter described, illustrated in one of its embodiments in the accompanying drawings, and particularly pointed out 75 in the appended claims.

Referring to the drawings, forming a part of this specification, Fig. 1 is a side elevation of the improved cam, and illustrating in particular the developed contour portion 80 for co-operating with the cam thrust receiving portion of the slide.

Fig. 2, an edge view of the same.

Fig. 3, a side elevation of the improved cam and cam operating handle detached 85 from the guide head or block.

Fig. 4, an edge view of the same illustrating in particular the arrangement and mounting of the cam between the spaced arms of the operating handle. 90

Fig. 5, side elevation of the wrench in assembled position, the working parts being in initial or extreme open positions preparatory to being moved to the article engaging or gripping position, one side of the guide 95 head being broken away for the purpose of clearer illustration of the parts.

Fig. 6, a similar view showing the parts in their extreme opposite or closed positions, the central or median dotted line $a-a$ and 100 the progressive dotted lines of the cam showing how the thrust between the latter and the engaged portion of the slide is centralized along the central longitudinal plane of movement between the relatively moving 105 parts thereby centralizing the strains and stresses and reducing the liability to damage or distortion of the parts to a minimum.

Fig. 7, a side elevation of the wrench with the parts in their intermediate position. 110

Fig. 8, a central longitudinal sectional view of the same, taken on line 8—8 of Fig. 7.

Similar numerals and reference designate 5 like parts throughout all the figures of the drawings.

The improved wrench comprises a suitable 10 guide head or block 1 of any suitable and convenient form, but in the present instance, comprising a metallic casing made up of sheet metal forming spaced parallel extending side walls and end walls, and open at its opposite ends to form a suitable guide way for the reciprocating slide and cam 15 hereinafter referred to.

One end of guide head of block 1, is adapted 20 to form an abutment for engaging one side of the nut or article to be operated upon, said abutment, in the present instance, being in the specific form of a filler block or anvil 25 1^a, secured, in the present instance, between the ends of the side wall by means of attaching elements or rivets 1^b.

The improved slide 2, is adapted to fill the 30 guideway of the guide block 1, and is provided with a nut engaging loop 2^a, projecting from one end of the guide block and arranged in co-operative relation to the abutment 1^a.

35 The inner sides 2^b, of the loop are preferably arranged at an angle of about 120°, corresponding to the common angles of the sides of the ordinary hexagonal nut, and the eye of the loop 2^a preferably terminates in a recess 2^c, corresponding in form to the filler block 1^a, and being adapted to receive the latter when the slide and loop are in their extreme extended or projected positions as in Fig. 5 of the drawings preparatory to being passed over the nut or other article to be grasped in giving the same a working motion or impulse.

It will be seen upon reference to the drawings that the engaging abutment 1^a and loop 45 2^a are arranged along the common longitudinal median plane or axis or movement of the slide and guide members and that the nut engaging parts are adapted to centralize the nut or other article to be operated upon thereby centralizing and distributing the 50 sereffes incident to grasping and moving the article being held and turned by the improved wrench.

As a means of reciprocating the slide 2, in the act of moving the nut engaging loop 55 2^a toward and from the nut engaging abutment 1^a, in the act of grasping and releasing the nut or article being operated upon, and particularly as a means of arranging the 60 cam thrust receiving portion of the slide and active face of the cam along the common median longitudinal plane of relative movement of the slide and guide members in their varying positions incident to engaging nuts or articles of varying sizes or forms, the

slide 2 is provided with a centrally located or median cam thrust receiving portion 2^d adapted to be engaged by a developed cam face 4^a of a cam 4, interposed between the side walls of the casing or block 1, and pivoted by means of a pivot bearing opening 4^c mounted on a bearing member 5. As a means of positively returning or projecting the slide 2, and loop 2^a, the cam thrust receiving portion 2^d, is preferably formed as a 75 part of a cam receiving opening 2^e arranged to be engaged by the nose portion 4^b of the cam when the latter and the handle are returned to their initial positions as indicated by dotted lines in Fig. 5 of the drawing. 80

As a means of engaging and operating the cam 4, and particularly as a means of centrally distributing the strains and stresses incident to use, a handle 6 is provided, said handle 6 being provided with oppositely arranged spaced arms 6^a, to receive the cam 4, and provided with fastening elements 6^b on either side, preferably in the form of spot welds or in the form of through bolts or rivets at the places indicated at 6^b. In the 90 present instance the handle 6, is made up of two sheet metal stampings of suitable contour at edges to form the rounded handle, and connected by means of fastening elements or rivets 6^b. 95

The arms 6^a of the handle preferably extend within the sides of the casing or guide block 1, and are preferably also mounted on the bearing member 5, and as a means of limiting the movement of the handle within the guide head of block 1, the upper edges of the ends of the casing are arranged to form stop members 1^c for engaging in the edges of the handle arm 6^a.

Having thus described one of the embodiments of my invention, without having attempted to set forth all the forms in which it may be made, or all the modes of its use, what I claim and desire to secure by Letters Patent, is,—

1. In a wrench, a guide head, a slide having a nut engaging portion longitudinally movable in said head and provided with a median cam receiving bearing portion, a cam pivoted on said head and operable against 110 said cam bearing portion of said slide, and a handle for operating said cam.

2. In a wrench, a guide head provided with a nut engaging abutment, a slide provided with a nut engaging portion, projecting from said head and provided with a cam opening, a cam pivoted in said head and operable in said cam opening, and a handle pivoted on said guide head for operating 115 said cam.

3. In a wrench, a head provided with a guide way, a handle provided with spaced arms pivoted within said head, a cam between said arms, a slide extending between the arms of said handle and provided with a 130

central cam thrust receiving portion, said slide being provided with a projecting portion adapted to engage and clasp a nut against said head.

5 4. In a wrench, a head provided with a guide way, a handle provided with spaced arms pivoted within said guide way, a cam between and secured to said arms, a slide within said guide way and extending between the arms of said handle and provided with a cam opening surrounding said cam, said slide being provided with a loop head projecting beyond said head and adapted to engage and clasp a nut against the latter.

15 5. In a wrench, the combination with a head block provided with a guide way, and a slide in said guide way provided with a nut engaging portion projecting from said head block and adapted to engage and draw the nut into engagement with an adjacent edge of said head block, and a cam in said head block engaging said slide along the longitudinal axial plane of movement of said head block and guide.

25 6. A wrench, comprising a head block provided with a nut engaging abutment, a slide longitudinally movable in said head block provided with a nut engaging loop movable toward and from said abutment, said slide being provided with a cam thrust receiving portion along the common longitudinal plane of said abutment and the plane of movement of said loop, a cam pivoted in said head on one side of said plane and provided with a curved contact portion engaging said thrust receiving portion of said slide along said longitudinal plane, and a handle having a limited movement in said head for positively actuating said cam and slide in either

40 direction.

7. A wrench, comprising a head provided with a nut engaging abutment, a slide in said head provided with a nut engaging member movable toward and from said abutment, said slide being provided with a cam thrust receiving portion along the common longitudinal plane of said abutment and nut engaging member, a cam pivoted in said head on one side of said plane and provided with a curved contact portion developed to engage said thrust receiving portion of said slide along said plane, and a handle having a limited amount in said head for actuating said cam.

8. A wrench, comprising a head having parallel extending side walls forming a guideway, a slide filling said guideway and provided with a cam receiving opening closed by said head and having a thrust receiving portion at the median portions of said head and slide, a nut engaging member at one end of said head and arranged at the transverse center of said guideway, said slide being provided with a loop surrounding said nut engaging member and having converging sides adapted to centralize and clamp a nut between the latter and said nut engaging member, and a handle connected to said cam for operating the same.

9. A wrench comprising a guide head having parallel extending sides forming a guideway, a slide in said guideway provided with a cam receiving opening closed by said sides and having a thrust receiving portion at the common axial plane of movement of said guide head and slide, a nut engaging member at one end of said head and arranged at the transverse center of said guideway, said slide being provided with a loop surrounding said nut engaging member and having converging sides extending at an angle of approximately 120° and adapted to centralize and clamp a hexagonal nut between the latter and said nut engaging member, and a handle on said cam for operating the same.

10. A wrench, comprising a head provided with a nut engaging abutment at one end and intersected by a guideway, a slide in said guideway provided with a nut engaging loop projecting from one end and movable toward and from said abutment, said slide being provided with a cam thrust receiving portion at the common longitudinal axial plane of movement of said head and slide, a cam extending across said guideway and pivoted in said head at one side of said axial plane of movement, said cam being provided with a contact portion engaging said thrust receiving portion of said slide in said common longitudinal axial plane in the varying longitudinal positions of the latter, and a handle provided with spaced arms extending on either side of said cam and arranged between the sides of the latter and the sides of said head.

In testimony whereof I have affixed my signature.

JAMES WEBB SAFFOLD.
